PINCH ROLLER HUB FOR A TAPE RECORDER OR THE LIKE

John H. Rentschler, Minneapolis, Minn., assignor to
Minnesota Rubber Company, Minneapolis, Minn.

Term of patent 14 years

Filed May 29, 1969, Ser. No. 17,416

Int. Cl. D14—01

U.S. Cl. D26—14

FIG. 1 is an end elevational view of a pinch roller hub for a tape recorder or the like, embodying my design;

FIG. 2 is a side elevational view thereof; and

FIG. 3 is a sectional view thereof taken on line 3—3 of FIG. 1.

An end elevational view taken from the end opposite that shown in FIG. 1 is substantially a mirror image thereof.

A side elevational view taken from any one of the sides other than that shown in FIG. 2 is substantially a mirror image thereof.

I claim:

The ornamental design for a pinch roller hub for a tape recorder or the like, as shown and described.
